UNITED STATES PATENT OFFICE.

THURE DAHL, OF NEW YORK, N. Y., ASSIGNOR TO LIGHTOLIER COMPANY, A CORPORATION OF NEW YORK.

DESIGN FOR A PLATE FOR WALL BRACKETS FOR LIGHTING FIXTURES.

61,188.

Specification for Design.

Patented July 11, 1922.

Application filed February 10, 1921. Serial No. 444,035. Term of patent 3½ years.

To all whom it may concern:

Be it known that I, THURE DAHL, a subject of the King of Sweden, residing at New York city, in the county of New York and State of New York, have invented a new, original, and ornamental Design for Plates for Wall Brackets for Lighting Fixtures, of which the following is a specification, reference being had to the accompanying drawing, forming part thereof.

The figure is a plan view of a plate for wall brackets for lighting fixtures showing my new design.

I claim:

The ornamental design for a plate for wall brackets for lighting fixtures as shown.

THURE DAHL.
